[57] **CLAIM**

The ornamental design for a magnetic disc storage container, as shown and described.

DESCRIPTION

FIG. 1 is a perspective view of a magnetic disc storage container showing my new design with its cover in the open and display position;

FIG. 2 is a right side elevational view thereof;

FIG. 3 is a top plan view thereof with the cover in the closed position;

FIG. 4 is a bottom plan view thereof;

FIG. 5 is an enlarged scale cross-sectional view taken along line 5—5 of FIG. 3;

FIG. 6 is a right side elevational view of FIG. 3;

FIG. 7 is a front elevational view of FIG. 3; and

FIG. 8 is a rear elevational view of FIG. 3.

FIG. 1

FIG. 2

FIG. 3**FIG. 4**FIG. 5

FIG. 6

FIG. 7

FIG. 8
